(57) **CLAIM**

The ornamental design for a digital audio disc player with radio tuner for automobile, as shown and described.

DESCRIPTION

FIG. 1 is a perspective view of the front, top and left side of digital audio disc player with radio tuner for automobile showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the front, top and left side of digital audio disc player with radio tuner for automobile in an opened position.

The broken lines shown are included for the purpose of illustrating the unclaimed portions of the digital audio disc player with radio tuner for automobile and form no part of the claim.
